UNITED STATES PATENT OFFICE.

ALBERTO ANDREA GIGLI, OF BIRMINGHAM, ENGLAND.

DOUBLE-ACTING INTERNAL-COMBUSTION ENGINE.

Application filed July 30, 1926, Serial No. 126,049, and in Great Britain August 10, 1925.

This invention relates to double acting internal combustion engines wherein cylinders have been arranged side by side, and in pairs the ends of the cylinders having common 5 combustion chambers and the pistons of such an engine driving through common gearing on to the crankshaft; and this invention has for its object an improved construction of such engines.

10 This invention can be adapted to horizontal, vertical, or V type engines; of either two stroke or four stroke cycle.

The present invention comprises essentially a double-acting engine in which the 15 cylinders are cast in pairs, or series of pairs, with cylinder heads or combustion chambers at both ends.

The cylinder heads or combustion chambers are detachable, the combustion space in 20 each cylinder head being common to two cylinder bores or expansion chambers.

Each pair of cylinders which are cast in one block, are arranged with slots or passages through the inner and outer walls, so 25 that the gudgeon-pin can be passed through the outer walls into the piston in the first cylinder, and then through the inner walls into the second piston in the adjacent cylinder, so that the pistons in each pair of cylinders work unitedly on a common gudgeon- 30 pin.

The pistons are double-headed or twin-type arranged to withstand high pressure at both ends, and the mounting of the aforementioned gudgeon-pin is midway between 35 the piston heads, the pistons being free or fully floating on the gudgeon pin.

The connecting rod is mounted on the central portion of the aforementioned gudgeon- 40 pin and thus transmits the power developed on the four piston heads. Alternatively the gudgeon-pin could be extended, and supported by two connecting rods, one at each outer side.

45 In the accompanying drawings Fig. 1 is a sectional elevation showing cylinders and pistons as described, adapted to a horizontal engine made in accordance with this invention. The left hand set of cylinders show a section on "AA", and the right hand cylinders show a section on "BB" as Fig. 2.

Fig. 2 is a sectional plan on CC, and DD of Fig. 1; the section on DD shows the pistons in full.

50 Fig. 3 is an end view of the cylinder block at E, Fig. 1.

Fig. 4 is an end view of the cylinder block at E, Fig. 1.

Fig. 5 is a section through gudgeon-pin and pistons, showing the alternative method 60 of using two connecting rods.

Fig. 6 is an end view showing the combustion head in the alternative method of using two connecting rods.

Referring to Fig. 1 and Fig. 2, which illustrate a double-acting internal combustion engine of the horizontal type, embodying two cylinder units opposed to each other; each cylinder block *a* has two bores *b* *b'* and *c* *c'*; the ends or faces of the cylinder blocks at *d* 70 and *e* are each machined to carry removable combustion heads *g* and *f*.

The face of the cylinder block at *e* is extended for mounting the crank chamber, this same face also forms oil joint for return of 75 lubricant.

The combustion heads *f*, *f* are located between the casing in which is arranged the main crank shaft and the cylinder blocks *a*, the inner ends of the cylinders in which are 80 closed by the said heads. This arrangement makes for compactness in the construction of the engine and also permits a ready access to the inner ends of the cylinder blocks and of the pistons therein by the removal of the 85 heads.

The combustion space in head *f* is common to the two bores *b* and *c*; and similarly the combustion space in head *g* is common to bores *b'* and *c'*. The combustion space in 90 each of the heads *g* and *f* communicates with the bores in the cylinder block through ports that are each controlled by one set of valves only, thus assuring that at all times, and under all conditions, the pressure on each of 95 the piston heads which work unitedly shall be equal.

The pistons *m* and *n* are twin-type having a head at each end, *h*, *j* and *k*, *l*. The pistons are packed or ringed at *p*, *q*, *s*, *t*. As the connecting rod works in a separate chamber from the cylinders, the crankshaft can be offset as shown at *r*, and the additional thrust so caused will be taken by the pistons and piston rings, particularly the rings at *s* and *t*, which are adjacent to the gudgeon-pin 105 boss.

The packing or rings are also used to effect positive lubrication of the cylinder walls and pistons. The oil is fed directly into the cylinder at *u* either by direct communication to the oil pump, or as an overflow from the cam 110

shaft chamber v , the piston rings at s , and t , being arranged to cut off the oil at a suitable point.

When the piston moves on the out-stroke, 5 the rings s sweep the oil up the cylinder. When the piston moves on the instroke the oil is returned by the rings at p , and passes out of the cylinder by the slot or passage w .

The flow of oil is also the means of cooling 10 the piston skirt.

The oil now flows back to the crank-chamber or the like via the duct x ; a baffle can be fixed at y so that the oil is delayed.

The duct x is so arranged that the cooling 15 water is admitted to circulate about the cylinders from an adjacent chamber through a port z ; thus the temperature of the oil is reduced before it returns to the crank-chamber.

The gudgeon pin marked a^2 is a hollow pin 20 of the fully floating type. This may also be arranged as a semi-floating pin, in which case it would be fixed in the connecting rod, and floating in the pistons. The fully floating pin would be kept in position by a spring ring 25 or any other method usually employed for this purpose.

The cylinders are arranged with slots or 30 spaces b^2 in the inner walls, so that the gudgeon pin can reciprocate carrying both pistons m and n . These slots or spaces are arranged to give clearance to the gudgeon pin, and connecting rod small end. The cylinders also have slots or spaces c^2 in the outer walls, so that by removing covers d^2 35 and e^2 the gudgeon-pin may be dismounted. Thus by dismounting the gudgeon-pin, and removing the detachable head, the pistons may be withdrawn, without disturbing any other part of the engine.

40 Referring to Fig. 3 this illustrates the end view of the cylinder block a , and shows the combustion head f , which is shaped at f^2 to allow passage of the connecting rod. The connecting rod reciprocates in the chamber 45 between the cylinders open to the crank-chamber. The opening to the crank-chamber is shown marked g^2 ; this passage or opening is enlarged at the bottom, to allow the small end of the connecting rod to pass when 50 mounting or dismounted.

The openings of the oil returns (ducts x) 55 are shown marked h^2 . The passage or space j^2 is arranged for mounting driving mechanism to the cam-shaft.

Fig. 4 shows the combustion head g .

The water inlet port k^2 receives the cooling water for the cylinders, which as described is adjacent to the oil return ducts, the water then passes up round the cylinders, and

returns to the cooling system via a port in 60 each combustion head. The cam shaft n^2 Fig. 1 is mounted in a chamber integral with cylinder block, and operates valves m^2 .

Referring to Figs. 5 and 6 which illustrate an alternative method; one connecting rod at each end of gudgeon pin. 1 are connecting rods, 2 are the pistons, 3 the combustion head, 4 the passages or spaces in which the connecting rods reciprocate, and 5 the 65 openings of the oil return ducts. 70

Claims:

1. In a double-acting internal combustion engine, cylinders constructed in pairs with detachable cylinder-heads at each end, a combustion chamber common to two cylinder bores formed in each head, pistons connected in pairs upon a common gudgeon pin and operating in unison within said cylinders, and means for obtaining access to said gudgeon pin for removal thereof. 75 80

2. In a double-acting internal combustion engine, cylinders cast in pairs, a casing in which is arranged the crank shaft of the engine located between the two pairs of cylinders, detachable heads at each end of said cylinders, the heads at the inner ends of the cylinders being between the cylinders and the crank shaft casing, a combustion chamber in each head common to two cylinder bores, and pistons mounted in pairs freely upon one 85 gudgeon pin so as to reciprocate in unison, there being passages in the inner and outer walls of the cylinders for permitting removal of the gudgeon pin. 90

3. In a double-acting internal combustion engine, cylinders constructed in pairs, detachable heads at each cylinder end, a combustion chamber in each head common to two cylinders, pistons mounted in pairs upon a common gudgeon pin and operating unitedly in pairs, means of access to said gudgeon pins from the exterior of the cylinders, a single connecting rod, and a chamber between each pair of cylinder bores in which the connecting rod 95 operates. 100 105

4. In a double-acting internal combustion engine, cylinders in which move double-ended pistons, a crank casing located intermediate the said cylinders, and detachable cylinder heads in which are formed combustion chambers closing the opposite ends of the cylinders, the heads at the inner ends of the cylinders being between the latter and the crank casing and each bodily removable to open the inner ends of the cylinders and expose the pistons 110 115 therein at their inner ends.

ALBERTO ANDREA GIGLI.
